W. M. Start
ATTORNEY.

UNITED STATES PATENT OFFICE.

JOHN R. REPLEGLE, OF DETROIT, MICHIGAN, ASSIGNOR, BY MESNE ASSIGNMENTS, TO ELECTRIC REFRIGERATION CORPORATION, OF DETROIT, MICHIGAN, A CORPORATION OF MICHIGAN.

REFRIGERATING UNIT.

Application filed April 19, 1926. Serial No. 102,928.

This invention relates to refrigerating units, and more particularly to the construction and mounting of water circulating tubing in a condenser chamber, the present invention being in the nature of an improvement in and relating to certain parts of a refrigerating unit invented by me, and for which an application for Letters Patent of the United States was filed on June 6, 1921, Serial No. 475,344.

In refrigeration systems in which water circulating piping is utilized for condensing refrigerant gas in a chamber of relatively small area having the compressor extending into and forming the inner wall thereof, it is necessary that the piping be coiled in close proximity to and around the compressor to provide sufficient heat transferring surface.

Vibration of the coiled pipe against the walls of the chamber will cause noise, and excessive vibration will tend to cause separation of the piping at its connection with the wall of the chamber which will permit leakage of the refrigerant from the system. The water piping is generally formed of a soft material to permit heat being readily transferred therethrough and vibration or displacement of the piping within the chamber will cause the piping to become cut or worn through due to contact with the compressor which is formed of harder material and has sharp exterior edges.

An object of my invention is to provide a shield for the compressor which is mounted so that water circulating piping within a chamber of small area will not rub or be cut against the compressor and thereby prevent water leakage in the condensing chamber of a refrigerating system.

A further object of my invention resides in the manner of forming and mounting a maximum length of water circulating piping in a condensing chamber of the character described to prevent misplacement of the piping and also vibration thereof against the walls of the chamber when the compressor is in operation.

Other objects of my invention will more clearly appear from the following description which, taken in connection with the drawings, comprises a disclosure of the preferred form of my invention; it being understood, however, that my invention includes

such variations and modifications of the particular embodiment thereof illustrated as come within the scope of the concluding claims.

In the accompanying drawings forming a part of this specification:

Figure 1 is an elevation of a portion of a refrigerating unit, partially in section, showing a compressor, condensing chamber and water coils within the condensing chamber; Figure 2 is a plan view of the compressor shield for the water coils; Figure 3 is a section of the shield taken on line 3—3 of Figure 2; and Figure 4 is an elevation of the water coil, as extended when removed from the condensing chamber.

Referring now to the drawings in detail, 70 Figure 1 represents a crank case which terminates at its upper end in a wall 11. This wall extends interiorly and exteriorly of the side walls of the crank case and provides a support for the dome 12 and the compressor 75 cylinder 13. A plurality of suitable resilient supports, such as shown at 14 can be provided beneath the crank case when desired.

The dome 12, is preferably formed of 80 copper sheeting which is provided at its base with a flange 15, which rests upon and is supported by the upper surface of the exterior portion of the wall 11. A ring 16 is placed over the flange 15 of the dome, 85 and bolts 17 are extended through the ring, dome flange and crank case wall and are drawn down in leak proof position by nuts 18.

The inner edge of the wall 11 provides an 90 aperture 18^a through which the compressor cylinder 13 projects, and an annular flange 19 formed integral with the cylinder extends over the wall 11, and is secured therewith by bolts 20 which are drawn down by 95 the nuts 21. The upper end of the cylinder is open and terminates in a laterally extending annular flange 22 upon which a cylinder head 23 is secured by cap screws 24.

The cylinder head is provided with a cylindrical vertically extending body 25 formed with a central inlet port 26 which opens into the cylinder 13, and with a plurality of outlet ports 27 leading from the inlet port through the upper end thereof. 105 The body of the head is also provided with

a central aperture in which a valve element 28 is slidably mounted. A support 29 is secured to the cylinder head by cap screws 30, and suitable springs are positioned within 5 the valve, to normally maintain the valve closed against the inlet port 26. A stop member 33 is also associated with the valve and support to limit the distance the valve can open, such stop member being threaded 10 at its upper end through the support 29 so that its position can be adjusted.

A piston 34 is mounted within the compressor cylinder and is provided with a valve in its head, not shown, through which 15 refrigerant gas passes on the down stroke. It will be understood that gas passes from an evaporator into the crank case, is compressed in the cylinder and discharged therefrom into the closed condenser chamber 20 formed by the dome 12, the walls 11 of the crank case, the flange 19, and the exterior wall of the cylinder and cylinder head above the flange 19. The compressed gas is condensed by its contact with the water 25 circulating piping in the dome and collects in the lower portion of the condenser chamber in liquid form serving to cool the cylinder, and passing from the chamber through a suitable outlet to the evaporator. The piston 34 is reciprocated by the rod 35 which 30 is driven in any conventional manner.

The system of refrigeration and the compressor mechanism described do not form the subject matter of this invention except 35 as they are associated with the condensing coils and their mounting which I will now describe.

In order to quickly and efficiently condense the compressed refrigerant gases discharged by the compressor in a condensing chamber of small area, as illustrated, which is generally commercially desirable, it is necessary that the water circulating pipe be coiled so that it will permit a maximum 40 length of heat transfer surface within the chamber. Another consideration in this connection is that it is highly desirable that such piping should be arranged with its major portion in a plane between the outlet of 45 the cylinder head and the top of the dome to obtain the greatest efficiency. In order to attain the highest efficiency of condensation within a small condensing chamber, I have formed the pipe in a plurality of nested 50 helical coils which are spaced from each other and lie in their whole or major part substantially above the outlet parts of the cylinder head. The inlet end 40 of the pipe is coiled upwardly about the cylinder at 41 55 and is continued above the cylinder as the inner coil 42 which is of an internal diameter greater than the external diameter of the body of the cylinder head. The pipe is next coiled downwardly forming the coil 43, 60 then upwardly again forming the coil 44,

and then downwardly forming the exterior coil 45, the end of which extends into and is secured in an aperture in the fitting 46. The end 40 of the coil is also secured in an aperture in the fitting 46 and the bosses 48 70 of the fitting extend through the wall of the dome and suitable water connections are made therewith.

The condenser tubing through which water is circulated in the condenser chamber, 75 is preferably formed of copper or a similar heat conducting material, which is helically wound in nested coils as above described. The convolutions of each coil are spaced and are normally extended so that they can 80 be compressed axially under tension when assembled in the condenser compartment. The tubing is made of softer material than the cylinder head about which it is assembled in close relation, and will be cut or 85 worn through by contact with the head or its securing cap screws during handling or by vibration, unless protected. To protect the tubing from such conditions, and to provide a bearing, I provide a cap 50 for the 90 compressor which encloses the head of the cylinder.

The cap 50 is preferably formed of sheet metal bent to provide a sleeve portion 51, 95 which extends around the central body portion 25 of the cylinder head and with a rim or flange extending laterally from the central body portion to cover the upper face of the cylinder head. The sleeve 51 extends axially beyond the upper end of the cylinder head and its end 52 is bent inwardly 100 sufficiently to enclose the cap screws 30. The gas from the outlet ports 27 of the cylinder head will pass through the sleeve into the condenser chamber, and the sleeve is 105 spaced from the portion 25 of the cylinder head permitting ready application or removal of the cap. The rim of the cap is bent to provide a curved upstanding head 53 which terminates in a downwardly bent edge portion 54 which rests upon and covers the peripheral edge of the cylinder head. The rim, intermediate the head 53 and the sleeve 51, is curved and forms an annular depression 55. This depression is formed to act 110 as a seat for the lower convolution of the coil 42 and to collect condensed gas, and apertures 56 are provided in the seat to direct the condensation so collected against the upper face of the cylinder head there- 115 beneath for cooling purposes.

The pipe coil in its extended form, as shown in Figure 4, is assembled in the dome with the inlet and outlet fitting 46 secured in leak proof relation with the dome wall and with the bosses 48 extending through suitable openings therein. The outer coil of the piping is of smaller diameter than the dome 12 adjacent thereto, and the upper convolutions of the coils 42 and 43 bearing 120 125 130

against the rim of the cap 50 and with the sleeve 51 extending interiorly of the coil 42, whereupon the dome is pressed toward the wall 11 until it bears thereagainst. The bolts 18 are then drawn down to secure the dome in leak proof relation with the wall 11.

The relation of the cap with the coil 42 and with the lower convolutions of the coils 10 42 and 43 will prevent lateral displacement of the piping at this point, and the convolutions of the coils 42 and 43 will be compressed and are under sufficient tension between the cap 50 and the dome wall to prevent lateral displacement of the entire piping. In this manner the coils will be securely positioned in a definite relation within the condensing chamber, and will still be sufficiently resilient axially to absorb the 20 vibrations of the compressor and its driving mechanism without displacement or rattling against the wall of the chamber. It will also be seen that the coils will be protected from contacting with the compressor 25 by the cap 50 so that they will not rub or be cut thereby.

What I claim is:—

1. In a refrigerating system of the character described, a closed condenser chamber 30 having a refrigerant outlet, a compressor opening into said chamber and forming an interior wall thereof, and water circulating piping extending through said chamber and formed in a plurality of nested helically wound coils, said piping being secured within said chamber by the tension of the inner coils against opposed walls of said chamber.

2. In a refrigerating system of the character described, a closed condenser chamber 40 having a refrigerant outlet, a cylinder extending within said chamber and having a head portion in communication with said chamber, said cylinder and head forming a portion of the wall of said chamber, and water circulating piping within said chamber formed in nested helical coils surrounding said cylinder and head, said coils intermediate said cylinder head and the opposite 45 wall of said chamber being under tension therebetween to secure said piping in a stationary relation within said chamber.

3. In a refrigerating system of the character described, a closed condensing chamber 50 having a refrigerant outlet, a compressor extending within and forming an interior wall of said chamber, said compressor having communication with said chamber, and water circulating piping wound in helical nested coils within said chamber, the interior coils of said piping being assembled in said chamber under tension to prevent displacement and bearing at one end against said cap at the other end against 60 the wall of said chamber.

4. In a refrigerating system, a closed condenser chamber provided with a liquid refrigerant outlet, a compressor cylinder extending into said chamber, a valved head secured to the end of the cylinder within 70 said chamber, an apertured cap member surrounding said cylinder head, and a water circulating pipe formed in helical resilient coils within said chamber and extending through a wall thereof, some of said pipe 75 coils being compressed between said cap member and a wall of said chamber, said cap member shielding said coils from contact with said cylinder head and providing a bearing therefor. 80

5. In a refrigerating system, a closed condenser chamber provided with a liquid refrigerant outlet, a compressor projecting into said condenser chamber and arranged to discharge compressed vaporized refrigerant, a shield cap on the end of said compressor in said chamber, said cap having an open upstanding sleeve portion and laterally extending base portion formed with an annular apertured gutter in which condensed vapor is collected and directed against the head of said compressor, and coiled water circulating piping under axial tension within said chamber and bearing against said shield cap and a wall of said 90 chamber. 95

6. In a refrigerating system, a closed condenser chamber having a dome forming the upper portion thereof, a compressor extending into said dome discharging compressed refrigerant vapor into said chamber, a sheet metal cap enclosing the head of said compressor, said cap being formed with an upstanding sleeve portion and a laterally extending flange depressed to provide an annular seat, and a water circulating pipe in said chamber extending through said dome, said pipe being formed in a plurality of nested helical coils, the innermost of said coils being compressed axially and bearing at one end within the seat in said cap and at the other end against the inner wall of said dome. 100 105 110

7. In a refrigerating system, a closed condenser chamber, a compressor extending into 115 said chamber for discharging compressed refrigerant into said chamber, an apertured cap enclosing the end of said compressor, and helically coiled water circulating pipe held under tension in a definite position within said chamber intermediate said cap and a wall of said chamber. 120

8. In a refrigerating system, a closed condenser chamber, a compressor extending into 125 said chamber for discharging compressed refrigerant into said chamber, an apertured cap enclosing the end of said compressor, and a helically coiled water circulating pipe held under tension in a definite position within said chamber intermediate said cap 130

and wall of said chamber, said cap being formed with a rounded exterior wall and spacing said coiled pipe from said compressor.

- 5 9. In a refrigerating system of the character described, a closed condensing chamber having a refrigerant outlet, a compressor extending within and forming an interior wall of said chamber, water circulating piping coiled within said chamber, and a cap intermediate said compressor and said coiled water piping, a portion of said water circulating piping engaging said cap under tension.
- 10 15. 10. In a refrigerating system of the character described, a closed condensing chamber having a refrigerant outlet, a compressor forming an interior wall of said chamber, said compressor having a passage therein 20 through which compressed refrigerant is directed into said chamber, water circulating piping coiled within said chamber, and a removable cap intermediate said compressor and said coiled water piping, a portion of 25 said coiled water piping engaging said cap under tension.
11. In a refrigerating system of the char-

acter described, a closed condensing chamber having a refrigerant outlet, a compressor forming an interior wall of said chamber, 30 said compressor having a passage therein through which compressed refrigerant is directed into said chamber, water circulating piping coiled within said chamber, and a shield element intermediate said compressor and said coiled water piping, a portion of 35 said coiled water piping engaging said shield element under tension.

12. In a refrigerating system of the character described, a closed condensing chamber 40 having a refrigerant outlet, water circulating piping coiled within said chamber, a compressor forming an interior wall of said chamber, said compressor having a passage therein through which compressed refrigerant 45 is directed into said chamber, and a cap having an exterior wall devoid of angular projections intermediate said compressor and said coiled water piping, a portion of 50 said coiled water piping engaging said cap under tension.

In testimony whereof, I hereunto affix my signature.

JOHN R. REPLOGLE.
